UNITED STATES PATENT OFFICE.

NORMAN F. DAHNE AND ANDREW L. THANOS, OF LA PORTE, INDIANA.

DISPENSING DEVICE.

Application filed February 28, 1924. Serial No. 695,651.

To all whom it may concern:

Be it known that we, NORMAN F. DAHNE and ANDREW L. THANOS, citizens of the United States, residing at La Porte, in the 5 county of La Porte and State of Indiana, have invented certain new and useful Improvements in Dispensing Devices, of which the following is a specification.

This invention relates to a device especially adapted for use in public places by means of which granular or powdered material may be dispensed in restricted quantities without waste and in a sanitary manner.

The invention has for its object the provision of a dispensing device which shall be of neat appearance, economical to manufacture and convenient and sanitary in use. Other objects will appear hereinafter.

The invention is exemplified in the combination and arrangement of parts shown in the accompanying drawings and described in the following specification and it is more particularly pointed out in the appended claims.

25 In the drawings;

Fig. 1 is a top plan view of a dispensing apparatus showing one embodiment of the present invention.

Fig. 2 is a vertical section of the device 30 shown in Fig. 1.

Fig. 3 is a horizontal section substantially on a line 3-3 of Fig. 2.

Fig. 4 is a fragmentary sectional view showing a detail of construction.

35 It is well known that in public eating places such as hotels and restaurants the use of the ordinary sugar bowl for dispensing sugar is both inconvenient and unattractive to the patrons and is likely to be unsanitary 40 as well. In the present invention means is provided for dispensing sugar in quantities corresponding approximately to the amount contained in the ordinary teaspoon. Of course, the amount dispensed at one time

45 may be regulated to suit conditions but since people are accustomed to measuring sugar in teaspoonfuls this is found to be a convenient quantity for each discharge of the apparatus.

50 In the form of invention shown in the drawing the numeral 10 designates an upright standard supported by a base 11 which is of sufficient extent and weight to prevent over-turning of the device. The standard

55 10 is preferably mounted to rotate in the base 11 so that the dispenser may be swung

into various positions to accommodate patrons at different positions about a table or other support. A container 12 is secured to the standard 10 by means of lateral arms 60 13. A central tubular member 14 extends vertically through the container 12 and is provided with openings 15 to admit material from the container 12 into the bottom portion of the interior of the tube 14. A plunger 16 is slidably mounted within the tube 14 and is provided with a peripheral groove 17 which registers with the openings 15. Below the groove 17 is a flange 18 which closes the lower end of the tube 14 and is provided 65 with an inclined upper face 19. A sleeve 20 is positioned within the tube 14 and has its upper end closed as shown at 21. The sleeve 20 is fixed to the inner face of the tube 14 by pins 22 which project into the interior of 70 the sleeve 20 in position to support a coil spring 23. The spring 23 surrounds a plunger rod 24 connected to the plunger 16 and extending upwardly through the end of the tube 14. The tube 14 and the sleeve 75 20 are slotted at one side as shown at 25 and a small rod or bar 26 projects laterally from the plunger rod 24 through the slot 25. The bar 26 passes through an opening 80 in the rod 24 as shown more clearly in Fig. 3, and the upper end of the spring 23 bears against the bar 26 to press the bar against the upper end of the slot 25 and thus retain the plunger rod 24 and the plunger 16 in their uppermost position.

85 The bar 26 is bent downwardly parallel with the outer surface of the tube 14 and is provided with a brace member 27. The horizontal portion of the bar 26 and the brace member 27 are soldered or otherwise 90 secured to a cover plate 28 which overlies the slot 25 and excludes the sugar from entering the slot 25. The bar 26 is extended downwardly and bent to form a stirring rod 29 surrounding the lower portion of the 100 tube 14. Whenever the plunger rod 24 is moved up and down the stirring rod 29 will agitate the sugar within the receptacle and prevent it from becoming packed and hardened. The upper portion of the receptacle 105 12 is closed by a lid 30 which may be held in place of a cap 31 which fits over the upper end of the tube 14 and is held in place by a bayonet slot 32 as shown more clearly in Fig. 4.

110 A removable knob 33 is threaded through the upper end of the plunger rod 24 and a

leather or other suitable washer 34 surrounds the rod 24 below the knob 33 to provide a yielding stop when the plunger is forced downwardly.

- 5 Whenever it is desired to obtain a quantity of sugar the knob 33 is moved downwardly into the broken line position shown in Fig. 2, this will carry the flange 19 downwardly to a position below the lower end of 60
 10 the tube 14 and permit the sugar contained in the groove 17 to be discharged. The upper portion of the plunger 16 closes the openings 15 during the discharge operation so as to limit the amount discharged. If 65
 15 more sugar is required a second operation will discharge a duplicate amount.

It is noted that the base member 11 is provided with depressions 35 to collect any sugar that may be accidentally spilled.

- 20 The standard 10 is also provided with a shelf 36 for supporting salt and pepper shakers 37 and a toothpick holder 38.

We claim:—

1. A dispenser for granular material 25 comprising a receptacle, a reciprocating plunger having a recess therein, said plunger being movable in said receptacle to bring said recess alternately into and outside of said receptacle, a rod for operating 30 said plunger, an agitator secured to said rod to move in unison therewith, a spring for moving said plunger in one direction, and a housing for said rod and spring to exclude the material in said receptacle from 35 contact with said rod and spring, said agitator being positioned outside of said housing.

2. A dispenser for granular material comprising a receptacle, a tubular member 40 within said receptacle, a plunger arranged within said tubular member to reciprocate therein, said plunger having a peripheral groove therein arranged to move into and out of registration with openings in said 45 tubular member, an agitator to engage said granular material and to move in unison with said plunger, and a spring within said tubular member for moving said plunger in one direction, said agitator being arranged outside of said tubular member.

3. A dispenser for granular material comprising a receptacle, a tubular member within said receptacle having a lateral opening at its lower end and within said 55 receptacle, a plunger within said tubular

member and having a peripheral groove arranged to register with the opening in said tubular member but movable to a position outside of said receptacle, a plunger rod connected with said plunger and extending outside of said receptacle, a spring surrounding said plunger rod within said tubular member, an arm connected with said plunger rod and extending outwardly through a slot in said tubular member, a stirring device carried on said arm, and a shield connected with said arm and covering the slot in said tubular member. 65

4. A dispenser for sugar comprising a receptacle having a tubular member extending vertically therethrough and having openings through the walls thereof within said receptacle, a plunger mounted to slide in said tubular member, a sleeve secured within said tubular member adjacent its upper end, a plunger rod extending upwardly from said plunger, pins extending through said sleeve and tubular member and projecting into the interior of said sleeve, a spring supported by said pins and surrounding said plunger rod, an arm secured to said plunger rod and engaging the upper end of said spring, said arm projecting laterally through a slot in said tubular member and sleeve, and a shield carried by 80 said arm and movable with said plunger and arranged to cover said slot. 85

5. A dispenser for sugar or the like comprising a receptacle having a tubular member extending therethrough and open at its lower end, said tubular member having lateral openings therein, within said receptacle, a plunger slidably mounted in said tubular member and having a recess for receiving the material through said openings and discharging said material from the lower end of said tubular member, a plunger rod connected with said plunger and positioned within said tubular member, a spring within said tubular member for moving said plunger rod in one direction, and a stirring device connected with said plunger rod and movable therewith to prevent clogging of the material within said receptacle. 90 100 105

In testimony whereof we have signed our names to this specification on this 21st day of February A. D. 1924.

NORMAN F. DAHNE.
ANDREW L. THANOS.
